UNITED STATES PATENT OFFICE.

CARROLL J. SHERMAN AND CHARLES H. SHERMAN, OF HOUSTON, TEXAS.

BURNER.

Application filed October 4, 1926. Serial No. 139,372.

This invention relates to new and useful improvements in a burner.

One object of the invention is to provide a burner of the character described specially 5 designed for the utilization of either oil or gas as a fuel and of such novel construction that it will readily vaporize the oil, when oil is used as a fuel.

Another object of the invention is to provide 10 a burner of the character described equipped with novel means for supplying air whereby a proper mixture of air and fuel may be at all times maintained to induce combustion of the fuel.

15 A further feature of the invention is to provide a burner of the character described equipped with a detachable combustion ring which will assist in the breaking up and complete combustion of the fuel used.

20 A still further feature of the invention is to provide a burner of the character described which is of simple construction and can be cheaply and easily manufactured and readily taken apart for cleaning and is 25 economical and efficient in use.

With the above and other objects in view this invention has particular relation to certain novel features of construction, operation and arrangement of parts, an example 30 of which is given in this specification and illustrated in the accompanying drawing wherein:—

The figure shows a perspective view of the burner, partly in section.

35 Referring now more particularly to the drawing the numeral 1 designates a stand which is supported by the legs 2 and which includes an upstanding tube 3 into which the fuel supply line 4 is connected. There is a

40 cup shaped support 5 screwed on to the upper end of the tube 3 and which encloses an air chamber 6. The central part of the bottom of this support is elevated, as at 7, forming a surrounding channel 8 provided

45 to receive any drippings of oil and the fuel collecting in this channel may be drained out through the drain pipe 9. Supported by the upper end of the support 5 there is an annular base 10 having spaced outer and

50 inner upstanding flanges 11 and 12 forming an annular channel 13 between them. Mounted on the base and detachable therefrom there is an annular outwardly flared

combustion ring 14. The base has a central spider consisting of radial arms 15 which 55 are formed integrally with the base and which are also formed integrally with and support the central downwardly elongated bearing 16. The fuel line 4, has the upward tubular extension 4' whose lower end is 60 threaded into the bottom of the support 5 and whose upper end extends through the bearing 16 and has a generator 17 screwed on to the upper end thereof and spaced above 65 the base 10. This generator is conical in general contour and has an internal chamber 18 with an outlet 19 at the apex of the generator and the outer surface of the generator is formed with a plurality of annular grooves 20 therearound. There is a generator cap 21 whose upper side is convex and whose under side is formed to conform to the external contour of the generator and this cap is fitted over the generator and is held spaced therefrom by suitable spacing 70 lugs, as 22. The fuel passes into the chamber 18 through the inlet line 4, 4' and is 75 partially heated therein and then passes up through the outlet 19 and flows down over the surface of the generator in a film between the generator and generator cap and is held by the grooves 20, so that it will be 80 thoroughly heated and vaporized in passing over the hot generator and will be discharged in the form of a vapor into the 85 channel 13 where combustion takes place. The film will be deflected outwardly against the combustion ring by the rim of the cap 21 and said ring will become very hot and further break up the unconsumed particles of 90 gas so that the fuel will be completely consumed.

The numeral 23 designates a supply gas line which leads to the usual pilot burner which may be utilized in case gas is used 95 as a fuel.

In case oil is used as a fuel it will trickle down around the generator and drop into the channel 13 in liquid state until the generator becomes hot enough to vaporize it. For 100 the purpose of preventing the oil from following along the underside of the generator and dropping into the chamber 6 the lower edge of the generator is provided with a plurality of spaced outwardly extending 105 projections 24 which are provided with the

grooves 25 which will lead the oil out to the points of the projections 24 where it will drop into the channel 13. After the generator becomes thoroughly heated the oil will 5 be vaporized and will thus be discharged in a circular sheet all around the generator.

The chamber 6 has an inlet opening 26, providing for the intake of air from the free atmosphere, or for the connection of a flue 10 leading from a conventional blow fan in case such blow fan is used.

What we claim is:—

1. A burner including a cup-like support having an air chamber therein, an annular 15 base on said support, a generator above said base having an internal chamber, a generator cap spaced above the generator forming a channel between them, an outlet connecting the generator chamber with said channel and 20 a fuel line terminating in said generator and having an outlet leading therefrom into said channel.

2. A burner including an annular base, a 25 detachable combustion ring thereon, a cup-shaped support sustaining said base and having an air chamber therein provided with an air inlet, a fuel inlet line leading up through the base, a hollow generator above said base and secured to the upper end of said line 30 and having an internal chamber into which said line discharges and provided with an outlet opening and a generator cap disposed above said generator and spaced therefrom and forming an annular channel with which 35 said outlet opening communicates.

3. A burner including an annular base having a central opening and having a channel around said opening, an outwardly flared combustion ring on said base, a cup shaped 40 support on which said base is mounted, said support having an air chamber provided with an air inlet, a central spider carried by the base and formed with a bearing, a generator having an internal chamber with an 45 outlet opening leading upwardly therefrom, a fuel inlet line extending up through said support and bearing and attached to said generator and terminating in the chamber therein and a generator cap fitted over said 50 generator and spaced therefrom.

4. A burner including a generator, a generator cap fitted over and spaced from the generator forming a channel between them, means for delivering fuel into said channel, 55 an annular base surrounding and spaced beneath the generator and having an upstanding outwardly flared rim removable therefrom and forming an annular combustion channel around said generator, the nipper 60 margin of said ring extending above the lower margin of said cap.

5. A burner including an annular base having a central opening and a channel around said opening, an approximately conical shaped generator disposed above said 65

opening and having a fuel duct leading through the apex thereof, the lower end of said duct being enlarged forming a fuel heating chamber, a generator cap fitted over the generator and spaced therefrom forming a 70 passageway between them which discharges into said channel, a fuel line disposed to discharge fuel into said chamber and to which said generator is attached.

6. A burner including an annular base 75 having a central opening and a channel around said opening, an approximately conical shaped generator disposed above said opening and having a fuel duct leading 80 through the apex thereof, a generator cap 80 fitted over the generator and spaced therefrom forming a fuel passageway between them which discharges into said channel, a fuel line disposed to discharge fuel into said duct and to which said generator is attached 85 and an outwardly flared removable combustion ring mounted on said base, and whose upper margin extends above the lower margin of the generator cap.

7. A burner including an annular base 90 having a central opening and a channel around said opening, an approximately, conical shaped generator disposed above said opening and having a fuel duct leading 95 through the apex thereof, and which is formed into a fuel heating chamber in said generator, a generator cap fitted over the generator and spaced therefrom forming a fuel passageway between them which discharges into said channel, a fuel line disposed to discharge fuel into said duct and to which said generator is attached and an outwardly flared combustion ring mounted on 100 said base and detachable therefrom the upper margin of the combustion ring extending above the lower margin of said cap.

8. A burner including an annular base having a central opening and outer and inner marginal upstanding flanges spaced apart 110 forming an annular channel between them, an outwardly flared combustion ring mounted on said outer flange, a spider in said opening, carried by said base, and having a central bearing, a fuel line extending through said bearing, a substantially conical shaped generator associated with the upper end of said line, and spaced above the base and having a fuel duct leading from said line upwardly therethrough, a generator cap fitted over said generator and spaced therefrom. 115

9. A burner including an annular base having a central opening and outer and inner marginal upstanding flanges spaced apart 125 forming an annular channel between them, an outwardly flared combustion ring mounted on said outer flange, a spider in said opening, carried by said base and having a central bearing, a fuel line extending through said bearing, a substantially conical shaped 130

generator associated with the upper end of said line and spaced above the base and having a fuel duct leading from said line upwardly therethrough, a generator cap fitted over said generator and spaced therefrom, a cup shaped support on which the base is mounted, said support having an internal air chamber and an air inlet leading into said chamber.

In testimony whereof we have signed our **10** names to this specification.
